UNITED STATES PATENT OFFICE.

HERMAN SCHWARZE AND FENN M. HOLDEN, OF DETROIT, MICHIGAN, ASSIGNEES TO
GENERAL MOTORS CORPORATION, OF DETROIT, MICHIGAN, A CORPORATION OF
DELAWARE.

LOCK-CONTROLLED SWITCH.

Application filed September 6, 1921. Serial No. 498,931.

This invention relates to lock controlled electric switches and the particular form of embodiment of the invention described hereinafter is an improvement on switches of the type disclosed in the patent to Kaisling No. 1,193,698, August 8, 1916. In the apparatus disclosed in the patent referred to a lighting switch includes a lever operable to several positions to control various lighting circuits of an automobile, and includes a lock for locking the lever in any of its positions either on or off.

In the present invention the general object is to provide an automobile lock switch controlling circuits in such a manner that the lighting of the car to comply with the law will not depend entirely on the memory of the driver. In carrying out this object we have provided that in order to find the key hole of the switch lock, the dash lamp and rear lamp may be lighted before the switch is unlocked; and that thereafter when the light switch is unlocked, the front lights will be automatically connected with the battery.

In the present invention one of the particular objects is to provide a lock controlled switch wherein the switch lever may be moved from one position to another without the switch being unlocked to allow movement of the switch lever to other positions.

Another object is to provide a lock controlled switch including an ignition switch and a switch for controlling other translation circuits such as lighting circuits of an automobile, wherein one locking device will lock the ignition switch lever in off position but will permit of limited movement of the other switch to certain of its positions, before the locking device is unlocked to permit movement of said other switch lever to other of its positions.

A further object is to provide a lock controlled switch wherein the ignition switch lever and lever for controlling other electrical translation circuits are controlled by a lock as stated in the preceding paragraph, and wherein the locking device may be locked only when the ignition switch is in the off position.

A further object is to provide a lock controlled switch for electrical translation circuits wherein a switch lever may be adjusted to at least three positions, movement of the lever from first to second positions being in-

dependent of the locking device, but movement to the third position being prevented by the locking device; and wherein movement of the lever from second to third positions may take place automatically when the locking device is unlocked.

Other and further objects of the present invention will be apparent from the following description, reference being had to the accompanying drawings, wherein a preferred embodiment of the present invention is clearly shown.

In the drawings:

Fig. 1 shows diagrammatically a plan of the switch embodying the present invention together with a wiring diagram of an ignition circuit and other electrical translation circuits; and

Figs. 2, 3 and 4 are diagrammatic views of certain parts shown in Fig. 1, showing these parts in various positions.

Referring to the drawings, a support 20 carries stationary contacts 21, 22, 23 and 24 connected respectively with grounded electrical translation circuits 25, 26, 27 and 28. Circuits 25, 26 and 27 include various lighting circuits of an automobile, and circuit 28 includes the ignition apparatus for the automobile engine (not shown). A movable switch contact 29 is rotatably supported by support 20 and is moved by lever 30. Contact 29 includes fingers 31 and 32. Contact 29 is connected by wire 33 and wire 34 with grounded battery 35.

To index the contact 29 in its various positions, a plate 36 having spaced lobes or lugs 37, 38, 39, 40 and 41 is provided. Plate 36 is attached to lever 30 so as to be rotated thereby when contact 29 is moved.

Ignition switch contact 46 is rotatably supported by support 20 and is actuated by lever 47. To index contact 46 in its positions, a plate 42 is provided with spaced lobes or lugs 43, 44 and 45.

Lever 50 is slidably and pivotally mounted on pin 51 secured to support 20 and carries rollers 52 and 53 cooperating with plates 36 and 42 respectively. Spring 54 bears at one end against lever 50 and is attached at the other end to a lug 55 carried by support 20, whereby yieldingly to maintain rollers 52 and 53 in engagement with said plates 36 and 42 respectively.

Locking bolt 60 is slidably mounted upon support 20, said support carrying studs 61

and 62 extending through slots 63 and 64 respectively provided in bolt 60. Bolt 60 is provided with lug 65 adapted to enter the notch 66 between lugs 37 and 41 of plate 5 33 or the notch 67 between lugs 40 and 41. Bolt 60 is provided with lug 68 adapted to enter the notch 69 between lugs 43 and 45 of plate 42. Obviously the bolt cannot be moved to locking position unless the contact 46 is in off position as shown in Fig. 1.

The bolt 60 is actuated by a key operated locking cylinder 70 journaled in a support 71. Cylinder 70 carries a pin 72 for engaging a stud 73 carried by bolt 60. As shown 15 in Fig. 1, bolt 60 is in unlocked position, but one counter clockwise turn of cylinder 70 will cause pin 72 to move bolt 60 to locked position shown in Figs. 2 and 3.

Starting with the bolt 60 in locked position, as shown in Fig. 2, ignition switch contact 46 will be locked since lug 68 will then be located in notch 69 of plate 42. The switch contact 29 may, however, be moved from the off position to its second position 20 of adjustment, or to its first circuit making or on position as shown in Fig. 3. This is possible since notch 66 is wide enough to permit finger 31 to engage contact 21 before lug 65 is struck by lug 41. When this occurs, 25 the dash lamp or instrument board lamp of the automobile will be connected with the battery 35, thus enabling the driver to find the keyhole in the locking cylinder 70 after dark.

Referring to Fig. 3, when contact 29 has been moved into its first on position, the detent roller 52 will be in the position shown wherein it has ridden over the point of lobe 39 and part way down onto the beveled camming surface 39^a. When the bolt 60 is moved into unlocked position shown in Fig. 4, the roller 52, being urged by spring 54 against the surface 39^a, will exert a pressure in such a direction as to produce clockwise rotation 45 of contact 29 so as to bring finger 31 into engagement with contacts 21 and 22. In this manner the automobile side lights will be automatically turned on. Therefore the driver need not remember to turn on the 50 side lights to comply with the city driving ordinances.

The fact that the driver cannot see the keyhole after dark makes him operate the switch lever to obtain light at the keyhole. 55 Since the rear lamp is on the same circuit with the dash lamp, the rear lamp will inadvertently be turned on. The unlocking of the ignition switch lever in order that the engine may be started turns on the side 60 lights. Therefore the external lighting of the automobile becomes automatic depending on the unlocking of the ignition switch after dark.

It is advantageous to place the rear lamp 65 on the dash lamp circuit for in some places

the lighting of the rear lamp only is necessary for parking. Locking the light switch so that the side and head lights cannot be turned on without authority prevents waste of battery current by meddlers.

By turning the contact 29 to its third on position when the roller 52 will engage in the notch between lobes 37 and 38, causes finger 31 to disengage contact 22 and to engage contact 23 to connect the head lamps 75 with the battery; and finger 32 will then engage contact 21 but not contact 22.

The ignition switch will be held resiliently in its off position, as shown in Fig. 1, by the engagement of the roller 53 in the 80 notch between lugs 44 and 45, and in the on position by the engagement of the roller in the notch between lugs 43 and 44.

While the form of mechanism herein shown and described constitutes a preferred 85 form of embodiment of the invention, it is to be understood that other forms might be adopted, all coming within the scope of the claims which follow.

We claim:

1. In mechanism of the class described, a movable member, locking means for preventing movement of said member beyond, but permitting movement to, a certain predetermined limit, and means positioned by movement of said member to said predetermined limit for causing further movement of said member when released from the locking means.

2. In mechanism of the class described, a movable member adapted to be adjusted to at least three positions, a lock-controlled device adapted to prevent movement of said member from the second position to the third, and means for retaining the member in any of the positions, said means operative to throw the member from the second position to the third when released from said lock-controlled device.

3. A control element having a first or neutral position and second and third positions in which it permits the actuation of mechanism, locking means preventing movement of said element to said third position but permitting movement to said second position, and means for moving said element from said second position to said third position upon release from said locking means.

4. A switch having an open position and two circuit closing positions, a lock adapted to permit movement from open position to the first circuit closing position but preventing movement to the second circuit closing position, and means operating upon the release from said lock to move the switch from the first circuit closing position to the second.

5. In an electric lighting system, a lock switch having an open position and two circuit closing positions adapted to control different lamps, a lock adapted to prevent

movement of said switch to the second circuit closing position but permitting movement from open position to the first circuit closing position, and means for moving the 5 switch to the second circuit closing position from the first when released from said lock.

6. A lock switch comprising a movable switch member, a plurality of contacts with which said member may engage successively, 10 means for retaining said member in a plurality of adjusted positions, and a lock-controlled device for preventing movement of said member beyond the first two positions, said retaining means being so constructed 15 and arranged as to throw said member from the second position to a succeeding position upon release from said lock-controlled device.

7. A lock switch comprising a series of 20 contacts, a switch member adapted to move successively into engagement with said contacts, a lock for said member permitting it to be moved from open position to engage the first of said contacts before being unlocked, a detent cooperating with said member to retain it yieldingly in its positions of adjustment, said detent being operative to move said member from the position in which it engages said first contacts upon release 30 from said lock.

8. In a switch, the combination with a plurality of stationary contacts each for connection with a current translation device, of a movable member for connecting one or 35 more of said stationary contacts with a current source, lock controlled means when in locked position permitting movement of said movable member to engage one of said contacts but preventing movement to engage the other contacts, and means for causing 40 said movable member to engage another of said contacts, said means being placed in condition for operation by the movement of said member into engagement with one of said 45 contacts and caused to operate automatically

when said lock controlled means is moved into unlocked position.

9. In a switch, the combination with a plurality of stationary contacts each for connection with a current translation device, of 50 a movable member for connecting one or more of said stationary contacts with a current source, lock controlled means when in locked position permitting movement of said movable member to engage one of said contacts but preventing movement to engage the other contacts, and means dependent on the movement of said movable member into engagement with one of said contacts and upon the movement of said lock controlled means 55 into unlocked position to cause said movable member to move automatically into engagement with another of said contacts.

10. In a switch, the combination with a plurality of stationary contacts each for connection with a current translation device, of 60 a movable member for connecting one or more of said stationary contacts with a current source, a lock controlled bolt, a plate movable with said member, said plate being 65 notched to permit movement of said member into or out of engagement with but one of said contacts when the bolt is in locked position, said plate being provided with spaced lobes, a spring pressed detent roller cooperat- 70 ing with said lobes to index said movable member, one of said lobes being so constructed that when said movable member has been moved to connect one of said contacts with the current source, said roller will ride 75 over the point thereof and part way into the next adjacent space beyond said lobe, whereby the movement of said bolt to unlocked position will permit said roller to move said movable member into engagement 80 with another of said stationary contacts.

In testimony whereof we affix our signatures.
